CLAIM

I claim the ornamental design for a machine tool for metal working, as shown and described.

DESCRIPTION

1. Machine tool for metal working
- 1.1 : Perspective
- 1.2 : Front
- 1.3 : Back
- 1.4 : Right
- 1.5 : Left
- 1.6 : Top
- 1.7 : Bottom

(Continued)

The broken lines show portions of the machine tool for metal working, which form no part of the claimed design.
